UNITED STATES PATENT OFFICE.

DAVID PELTON MOORE, OF WASHINGTON, DISTRICT OF COLUMBIA.

TELEPHONE-RECEIVER.

1,194,765.

Specification of Letters Patent. Patented Aug. 15, 1916.

Application filed July 30, 1913. Serial No. 781,990.

To all whom it may concern:

Be it known that I, DAVID PELTON MOORE, a citizen of the United States, residing at Washington, in the District of Columbia, have invented certain new and useful Improvements in Telephone- Receivers, of which the following is a specification.

This invention relates to improvements in telephone receivers, and more particularly to that type by means of which the sound is greatly amplified, without affecting the articulation, one object of the present invention being the provision of a receiver, in which the diaphragm is not unduly stressed and in which the armature is connected thereto by a lever, or system of levers, that multiply the vibratory movements of the diaphragm when the armature is affected.

A further object of the present invention is the provision of means for adjusting the coil, whereby the air-gap is varied without varying the stress upon the diaphragm.

A still further object of the present invention is the provision of means for adjusting the coil to vary the adjustment of the pole thereof relatively to the fulcrum point of the armature, thus to increase or decrease the distance of the magnetic effect thereof upon the armature.

In designs of receivers heretofore used in connection with "loud" telephones, both for announcing purposes and in connection with sound reproducing machines, the diaphragm has been placed under varying stresses, either by adjusting the lever connected to the diaphragm, or the armature to and from the pole of the coil to vary the air-gap. In these, the main objection lies, and this has been borne out by experiments, in the connection with the diaphragm that has either too great or too little flexing action upon the diaphragm, such effect either placing too great or too little stress upon the diaphragm. It has been discovered that the best results

are attained both as to loudness and articulation, when there is practically no stress upon the diaphragm, and also when the periphery of the diaphragm is clamped firmly and not mounted with one or more cushions.

In order therefore, to mount the diaphragm as above set forth with practically no stress thereupon, and to properly vibrate the same to produce the highest efficiency in sound reproduction, the armature is fulcrumed to one pole of a permanent magnet while the free end, which is connected to the lever or

levers for operating the diaphragm, is disposed to be above the pole of the coil or electro-magnet which is attached to be influenced by the remaining pole of the permanent magnet. This electro-magnet, however, is the adjustable member and is so mounted as to be moved to and from the armature to vary the air-gap and to and from the fulcrum point of the armature to vary the point of attack of the pole relatively to the armature.

To more clearly explain the manner of carrying out the above, attention is invited to the accompanying drawings, in which:

Figure 1 is a side elevation of the preferred form of receiver, partly in section, made according to and embodying the present invention. Fig. 2 is a view looking from above that as shown in Fig. 2. Fig. 3 is a section taken on line 3—3 of Fig. 1. Fig. 3^a is a detail view of the electromagnet and the means for varying the air-gap. Fig. 4 is a view partly in section of a system of levers for vibrating the diaphragm. Fig. 5 is a longitudinal section through a modified form of receiver employing two diaphragms and a central collecting chamber. Fig. 6 is an end view thereof. Fig. 7 is a section taken on line 7—7 of Fig. 5. Figs. 8 and 9 are detail views of the mounting for the electromagnet shown in Fig. 5. Fig. 10 is a view in elevation of the diaphragm chamber as shown in Fig. 1 with means for conveying and amplifying the sound vibrations at both sides of the diaphragm. Fig. 11 is a view illustrating the same principle as applied to the receiver shown in Fig. 5. Fig. 12 is a view similar to Fig. 4, in which the flat spring is dispensed with. Fig. 13 is a side elevation partly in section of still another modified form of receiver. Fig. 14 is a section taken on line 14—14 of Fig. 13. Fig. 15 is a section taken on line 15—15 of Fig. 13. Fig. 16 is a detail view showing the method of mounting the adjusting screw for the receiver shown in Fig. 13.

Referring to the drawings, and more particularly to Figs. 1, 2, 3, and 3^a, the numeral 1 designates a bi-polar permanent magnet of usual form, the terminal or pole 2 thereof being shorter than the pole 3, which is slightly reduced. The frame, composed of the arms 4 and 4', is supported from the magnet 1, and carries the inner member 5, which with the outer member 6 forms the support for the diaphragm 7. This dia-

phragm may be of mica, or phosphor bronze, both of which have been found excellent for this work. A rod or stem 8, is connected in the usual manner to the diaphragm, and is connected to the lever 9, which is pivoted at 10 to the arm 4', a flat spring 11, being seated in the free end of the lever 9 and mounted in the lug 12 carried by the arm 4. This spring may be dispensed with as shown in Figs. 4 and 12, but it has been found that it tends to maintain the lever 9 parallel with the diaphragm and to relieve the stress thrown upon the diaphragm. A plate 13 connects the lever 9 to the pin 14 carried by 15 and in the free end of the armature 15, whose point of fulcrum is upon the outer face of the reduced end of the pole 3, the lug 16 preventing the same slipping outwardly. The coil 17 has the outer end of its pole 18 disposed adjacent the armature 15, the end 19, as shown in Figs. 1 and 3^a, being projected within the space between the poles 3 and 2, and having an aperture 20, in which is mounted the eccentric or cam 21, keyed at 26, upon the stem 23. This stem is mounted for rotation within the exteriorly threading adjusting sleeve 24, mounted in the threaded bores 25 and 26, of the arm 4' and the pole 2, respectively. Thus by rotating the stem 23 the pole 18 is moved to and from the armature 15 and thus the air-gap is varied without affecting the relative position of the lever 9 and diaphragm. To move the coil laterally and thus move the end of the pole 18 near to or farther away from the pole 3, and thereby vary the fulcrum of the armature, the inner end of the sleeve 24 bears against the end 19 of the pole and is opposed by the cone spiral spring 28, which rests against the opposite side of the end 19 of the pole and the non-magnetic plate 29 in which the inner end of the stem 23 is seated. The recessed head 30^a of the sleeve 24 is milled so that the sleeve may be readily adjusted. The milled head 27 of the stem 23 is disposed for ready access.

In the form illustrated in Figs. 5, 6, 7, 8 and 9, the sound collecting chamber 30 has the horn attaching member 31 at one side the two diaphragms 7' and 7^a, being mounted 50 at opposite sides and properly clamped by the rings 5'. This receiver is a double one, and has two permanent magnets 32, of the watchcase type at opposite ends. One of the respective pole pieces 33 and 34, is provided with the fulcruming block 3', corresponding to the pole 3 heretofore described, supporting its armature 15', whose pin 14', is connected by the plate 13' to the lever 9'. This lever is supported at 10', and is connected to the diaphragm by the stem 8'. A flat spring 11' is mounted in the free end of the lever 9', and corresponds to the spring 11 heretofore described. A block 35 is mounted for sliding movement by means of the screw 36, while the screw 37 adjustably connects the inner

end 19' of the pole piece 18', of the coil 17' to the block. The inner end of the pole 18', as shown in Figs. 5 and 8, is mounted in the pole piece 34 of the magnet 32 for sliding movement, so that when the screw 37 is manipulated the air-gap adjacent the end of the pole 18' and the armature is varied. By manipulating the screw 36 the block 35 is slid and the pole 18' is moved to and from the pole 3' to vary the point of the armature 75 affected by the pole 18'.

In Fig. 4, two levers 9^a and 38 are interposed between the diaphragm 7^b and the armature 15^a the free end of the lever 9^a, being connected by the plate or rod 39 to the lever 38 nearer the fulcrum point of the lever 38, a stem 8^a connecting the free end of the lever 38 to the diaphragm clamped in the members 5^a and 6^a. Thus the coil 17^a affects the armature 15^a, which through the 85 rod 13^a, actuates the levers 9^a and 38, to multiply the distance of vibration in the diaphragm and consequently increase the loudness of tone given off thereby. The number of levers 38 may be varied.

As shown in Fig. 10, the chamber 6^b carries the amplifier tube 6^c for the main amplifier 47, while to collect the vibrations at the rear of the diaphragm a chamber 6^d is provided and leads into the sleeve 6^e and the 95 auxiliary amplifier 48.

In Fig. 11, the form of receiver shown in Fig. 5 is employed, the chamber 30', having its tube 31' attached to the main amplifier 44, the two auxiliary chambers 40 and 41 being connected to collect the sound vibrations from the outer sides of the two diaphragms (not shown) and through the tubes 42 and 43, convey them to the two auxiliary amplifiers 45 and 46, respectively.

By the arrangements as shown in Figs. 10 and 11, the greatest efficiency in sound collection is secured, these devices being particularly designed for use in connection with announcements at railroad stations and the like, and for talking and singing motion pictures.

In the form of receiver shown in Figs. 13, 14, 15 and 16, there is no provision made for varying the lateral position of the coil 17^b, relative to the fulcrum point of the armature 15^b, the member 49 of the permanent magnet having the armature fulcrum end 50, and being connected by the member 51, to slidably support the member 53 of the 115 permanent magnet, the spacing lug 52 of the member 51 and the adjacent portion of the magnet member 53 being provided with the sliding connection 54. The free end of the magnet member 53, is slidably connected in a similar manner at 56 and 57 to the spacing block 55 and the arm 4^a. In order to move the magnet member 53 and consequently vary the air-gap, a bore 58 is formed 125 in the end of the member 53, the threaded 130

nut 59 being slid in the slot 60 from the side to receive the adjusting screw 61. This screw is provided with the annular shoulder 62 at a fixed point, and this is rotatable within 5 in the bore 63 of the member 51, the thimble 64 with the operating end 65, locking the parts as shown in Fig. 16, so that the screw 61 may be manipulated by the milled head 66 to longitudinally slide the magnet member 53 and the coil 17^b.

What I claim, as new, is:—

1. A telephone receiver, including a permanent magnet, an armature, a diaphragm operatively attached to the armature, a coil 15 having its pole in attractive relation to the armature and under the influence of the permanent magnet, means adjustable at will for moving the coil to vary the air-gap between its pole and the armature, and means also 20 adjustable at will for moving the coil to vary the position of the pole relative to the fulcrum of the armature.

2. A telephone receiver, including a permanent magnet, a diaphragm, a support for 25 the diaphragm, a pivoted lever having its free end operably connected to the diaphragm, the pivot of the lever being fixed, an armature operably connected to the lever, a longitudinally and laterally slideable coil 30 connected to the permanent magnet and having its pole in attractive relation to the armature, and manually adjustable means for sliding the coil to vary its relation to the armature.

3. A telephone receiver, including a permanent magnet, a diaphragm, a support for the diaphragm, a lever having one end operably connected to the diaphragm, a fixed 40 pivot for the other end of the lever, an armature operably connected to the lever, a longitudinally and laterally slideable coil under the influence of the permanent magnet, and manually operable means for moving the coil to vary the air-gap between the pole 45 of the coil and the armature.

4. A telephone receiver, including a permanent magnet, a diaphragm, a support for the diaphragm, a lever having one end operably connected to the diaphragm, a fixed 50 pivot for the other end of the lever, an armature operably connected to the lever, a coil under the influence of the permanent magnet, manually operable means for moving the coil to vary the air-gap between the pole 55 of the coil and the armature, and a second manually operable means also for moving the coil to vary the position of the pole of the coil relatively to the fulcrum of the armature.

5. A telephone receiver, including a bipolar permanent magnet, one pole of which is longer than the other, a longitudinally and laterally slideable coil connected to the other pole of the magnet, an armature fulcrumed upon the longer pole of the perma-

nent magnet, a diaphragm operably connected to the armature, and manually operable means for sliding the coil to vary the air-gap between the pole thereof and the armature.

6. A telephone receiver, including a bipolar permanent magnet, one pole of which is longer than the other, a longitudinally and laterally slideable coil under the influence of the shorter pole, an armature fulcrumed upon the longer pole of the permanent magnet, a diaphragm operably connected to the armature, and manually operable means for moving the coil to vary the air-gap between its pole and the armature.

7. A telephone receiver, including a bipolar permanent magnet, one pole of which is longer than the other, a coil under the influence of the shorter pole, an armature fulcrumed upon the longer pole of the permanent magnet, a diaphragm operably connected to the armature, means for moving the coil to vary the air-gap between the pole thereof and the armature, and means for moving the coil to vary the position of the pole thereof relatively to the fulcrum point of the armature.

8. A telephone receiver, including a permanent magnet, a diaphragm, a longitudinally and laterally slideable coil having its pole under the influence of the permanent magnet, an armature under the influence of the pole of the coil, leverage multiplying means connecting the diaphragm and armature, and manually operable means for moving the coil to vary its relation to the armature without changing the relative positions of the armature and the diaphragm.

9. A receiver having a bipolar permanent magnet, an armature fulcrumed to one pole 105 and extending above the other pole thereof, an electromagnet, a longitudinally and laterally movable carrier for the electromagnet disposed in magnetic relation to the permanent magnet, and manually operable means 110 for moving the carrier and its electromagnet to vary the relation of the pole of the electromagnet to the armature.

10. A receiver, including a bipolar permanent magnet, one pole of which is longer than the other, an armature fulcrumed to the longer pole and extending toward the short pole, a diaphragm operably connected to the armature, a coil whose pole has an extension disposed between the two poles of the permanent magnet and in magnetic attraction only to the shorter pole, the outer end of the pole of the coil being in attractive relation to the armature, and manually operable means for connecting the coil through its pole extension to the shorter pole of the permanent magnet and for moving the coil to vary the relation of its pole 120 attractivity to the armature.

11. A telephone receiver, including a bi-

- polar permanent magnet, a coil under the influence of one pole thereof, an armature fulcrumed upon the other pole of the permanent magnet, a diaphragm operably connected to the armature, means for moving the coil to vary the air gap between the poles thereof and the armature, and means for moving the coil to vary the position of the pole thereof relatively to the fulcrum point of the armature.
12. A telephone receiver, including a permanent magnet, an armature actuated diaphragm, a coil slidably connected to the permanent magnet for longitudinal and lateral movements relative to the armature, and means for moving the coil.
13. A telephone receiver, including a permanent magnet, an armature actuated diaphragm, a coil slidably connected to the permanent magnet for longitudinal and lateral movements relative to the armature, manually operable means for imparting longitudinal movement to the coil, and a second manually operable means for imparting lateral movement to the coil.
14. A telephone receiver, including a diaphragm, an armature operably connected thereto, a bi-polar permanent magnet, one pole of which extends beyond the other to form a fulcrum for the armature, a coil disposed for longitudinal and transverse sliding movements between the poles and having its pole under the influence of the short pole of the permanent magnet, and means for moving the coil to regulate the position of its pole to the armature.
15. A telephone receiver, including a diaphragm, an armature operably connected thereto, a bi-polar permanent magnet, one pole of which extends beyond the other to form a fulcrum for the armature, a coil having its pole piece elongated and projected between the poles of the permanent magnet and in magnetic attraction to the short pole, means engaging the pole extension to hold it between the poles of the permanent magnet and for imparting longitudinal movement to the coil, and coöperable means engaging the extension upon opposite sides for holding it against transverse movement and for moving the coil to place its pole relatively to the fulcrum point of the armature.
16. A telephone receiver, including a diaphragm, an armature operably connected thereto, a bi-polar permanent magnet, one pole of which extends beyond the other to form a fulcrum for the armature, a coil having its pole piece elongated and projected between the poles of the permanent magnet and in magnetic attraction to the short pole, a spring interposed between the extension and one pole of the permanent magnet, an adjustable screw disposed to engage the opposite side of the extension to coöperate with the spring to regulate the position of the coil relatively to the fulcrum point of the armature, and oscillatory means engaging the extension to impart longitudinal movement to the coil to regulate the air gap between the armature and the pole of the coil.
17. A telephone receiver, including a diaphragm, an armature operably connected thereto, a bi-polar permanent magnet, one pole of which is longer than the other and forms a fulcrum for the armature, a coil having its pole piece extended and projected between the poles of the permanent magnet and in magnetic attraction to the short pole, a spring interposed between the extension and one pole of the permanent magnet, an adjustable screw disposed to engage the opposite side of the extension to coöperate with the spring to regulate the position of the coil relatively to the fulcrum point of the armature, said extension being provided with an opening therein, and a stem actuated cam mounted in said opening, whereby the oscillation of the stem and cam imparts longitudinal movement to the coil.

In testimony whereof I affix my signature in presence of two witnesses.

DAVID PELTON MOORE.
